US00D579017S

(12) **United States Design Patent**
Su

(10) **Patent No.:** **US D579,017 S**
(45) **Date of Patent:** **** Oct. 21, 2008**

(54) **TOP SHELL FOR PORTABLE BARCODE SCANNER**

(75) Inventor: **Fei-Ming Su**, Changhua County (TW)

(73) Assignee: **Universal Scientific Industrial Co., Ltd.**, Nan-Tou (JP)

(**) Term: **14 Years**

(21) Appl. No.: **29/282,579**

(22) Filed: **Jul. 24, 2007**

(51) LOC (8) Cl. **14-02**

(52) U.S. Cl. **D14/426**

(58) **Field of Classification Search** D14/420, D14/426-430, 453, 341-347, 412, 439, 137, D14/138, 191, 496, 147, 148, 247, 248, 144, D13/107, 184; 358/473; 235/462.43, 462.45, 235/462.47, 462.48, 462.44, 462.46, 487, 235/472.01, 472.02; 16/110.1, 430, 431; 439/133, 135; 709/219, 201, 224, 203; 710/73; 320/114, 115, 123; 361/679-683; 382/313, 382/321; 455/575.1-575.4, 561, 572, 414.1, 455/550.1, 417, 411, 556.2, 564, 566, 41.2, 455/418, 466, 90.1, 517; D18/2, 7, 11; D21/329, D21/517; 400/486, 472, 489; 341/20, 22, 341/26; 379/112.01, 368, 434, 433.01-433.13; 715/864, 780, 816; 248/918

(57) **CLAIM**

The ornamental design for a top shell for portable barcode scanner, as shown and described.

DESCRIPTION

FIG. 1 shows a perspective view of the present design.

FIG. 2 shows a right side elevational view of the present design.

FIG. 3 shows a top plan view of the present design.

FIG. 4 shows a front elevational view of the present design.

FIG. 5 shows a bottom plan view of the present design.

FIG. 6 shows a left side elevational view of the present design.

FIG. 7 shows a rear elevational view of the present design; and,

FIG. 8 is a schematic drawing showing that the present design is assembled with a bottom shell for a barcode scanner, in which broken line illustration in the drawing is for illustrative purposes only and forms no part of the claimed design.
